US0D1079884S

(12) **United States Design Patent** (10) **Patent No.:** **US D1,079,884 S**
(45) **Date of Patent:** **** Jun. 17, 2025**

(54) **GUN SIGHT**

(71) Applicant: **HUANIC CORPORATION**, Xi'an (CN)

(72) Inventors: **Jianhua Sun**, Shaanxi (CN); **Zhezi Zhang**, Shaanxi (CN)

(73) Assignee: **HUANIC CORPORATION**, Xi'an (CN)

(**) Term: **15 Years**

(21) Appl. No.: **35/520,622**

(22) Filed: **Mar. 8, 2024**

(80) **Hague Agreement Data**

Int. Filing Date: **Mar. 8, 2024**

Int. Reg. No.: **DM/236471**

Int. Reg. Date: **Mar. 8, 2024**

Int. Reg. Pub. Date: **Apr. 26, 2024**

(30) **Foreign Application Priority Data**

Sep. 11, 2023 (CN) 202330589942.8

(51) **LOC (15) Cl.** **22-01**

(52) **U.S. Cl.**

USPC **D22/109**; D26/60

(58) **Field of Classification Search**

USPC D22/108, 109, 110; D26/46, 51, 60

CPC F41G 1/35; F41G 11/004

(57) **CLAIM**

The ornamental design for a gun sight as shown and described.

DESCRIPTION

1. Gun sight

1.1 :Front

1.2 :Back

1.3 :Left

1.4 :Right

1.5 :Top

1.6 :Bottom

1.7 :Perspective

Reproduction 1.1 is a front view of a gun sight; reproduction 1.2 is a back view thereof; reproduction 1.3 is a left view thereof; reproduction 1.4 is a right view thereof; reproduction 1.5 is a top view thereof; reproduction 1.6 is a bottom view thereof; and reproduction 1.7 is a perspective view thereof. The broken lines in the reproductions disclose unclaimed portions of the gun sight only and form no part of the claimed design.

1 Claim, 7 Drawing Sheets
